UNITED STATES PATENT OFFICE.

HARLEY H. MONTAGUE, OF DENVER, COLORADO.

MACHINE FOR MANUFACTURING AND FINISHING FLOWERPOTS.

Application filed April 1, 1922. Serial No. 548,739.

To all whom it may concern:

Be it known that I, HARLEY H. MONTAGUE, a citizen of the United States, and resident of the city and county of Denver, 5 State of Colorado, have invented certain new and useful Improvements in Machines for Manufacturing and Finishing Flowerpots; and I do declare the following to be a full, clear, and exact description of the 10 invention, such as will enable others skilled in the art to which it appertains to make and use the same, reference being had to the accompanying drawings, which form a part of this specification.

15 The object of this invention is to provide a machine for the manufacture of flower pots and the like which will at the same time finish all the edges of the pots so that when discharged from the machine they will 20 be smooth throughout and may be handled even after drying and burning without danger of injury to the operator's hands from projecting burrs as has been the case heretofore. In the past, the joints in pot 25 making machines have been such as to form burrs during the forming operation which either had to be removed by another operation or if left caused injury to the operator's hands after drying and baking.

30 Briefly the invention comprises a pair of relatively movable members which cooperate with the dies or forming sections for the body of the pot, which members have opposed engaging faces portions at least of 35 which are disposed out of a plane perpendicular to the axis of the mold. In other words said faces form a joint which is somewhat irregular, with the result that the irregular portions serve as scraping or 40 cleaning means for the rotating pot being formed within the mold. Vents are preferably provided for surplus clay. Thus when the pot is discharged all edges and all portions opposite joints are clean and free from 45 burrs or surplus clay in any other form.

In the accompanying drawings wherein one embodiment of the invention is disclosed,

50 Fig. 1 is a vertical section through a machine equipped with the present invention;

Figs. 2 and 3 are perspective views respectively of the upper and lower relatively movable ring members which form the irregular cleaning joint.

The drawings disclose a standard 10 55 which carries a bearing arm 12 for a drive shaft 16 having a pulley 14 driven by a belt 15. The drive shaft 16 supports a spinner or rotating die body 18 which may have a separate bottom-forming member 19, the 60 parts being held by a bolt 20. Standard 10 has guides 26 on the sides thereof for a vertically reciprocable arm 27 which supports the lower die or cup 28 through the medium of a flange 128 resting upon said arm 27, 65 this die being vented at its shoulder forming portion as indicated at 29. The upper portion of die 28 carries a ring 30, and the lower portion carries a movable bottom-forming piece 32 provided with depending parts 34 70 which are vented at 35. This piece 32 also serves as an ejector, the lowermost end of a depending part 34 being adapted to engage with the floor or the like when mold 28 is lowered thereby causing the pot to be lifted 75 from the mold by said piece 32 whence it may be easily removed by the operator. The arm 27 is moved through the medium of a lifting link 36 operable by a lever 38 having a treadle 40 and pivoted at 42 to a base 44, 80 the arm 27 and its die 28 being returned to lowered position by gravity.

For cooperation with the ring 30 on the top of die 28, an upper ring 24 is secured at 25 to a relatively stationary arm 22 carried 85 by standard 10. Ring 24 is provided with a preferably beveled flange 45 whose edge is more or less cam shape and presents low portions 46 and high portions 48 connected by long curves, clay vents 50 being formed 90 in the high portions. Within the flange an annular groove 52 is formed which is approximately semi-cylindrical in cross section and forms the top edge of the pot. Within the groove 52 the ring 24 has an 95 annular bearing surface 54 for rotative engagement of the shoulder of spinner 18, an upper extension of spinner 18 bearing within the ring 24 as indicated at 118 and being centered thereby. Without the groove 52, 100 the edge of flange 45 is in the form of an engaging or joint-forming face 53 which however is relatively narrow as shown.

The ring 30 is provided with a flange 55 similar to flange 45 and having low portions 56 and high portions 58 to cooperate respectively with the high portions 48 and the low portions 46 of the ring 24, and is

vented at 60 in the high portions 58. The flange 55 is beveled as is flange 45 and its edge presents a narrow engaging or joint-forming face 62 to cooperate with face 53 of ring 24.

In operation the clay is placed in the cup 28 and the latter elevated more or less gradually until face 62 engages face 53, the spinner die 18 being meanwhile rotated. The surface 10 plus clay works out through the various vents 35 and 29 and between the faces 53 and 62 until the latter engage whereupon any surplus will escape through vents 50 and 60. The rotation of the spinner 18 also 15 causes rotation of the pot being formed which carries the pot past the various edges of the high and low portions 46, 48, 56 and 58 of the two rings, and also past the edges of the vents 50 and 60. The result is a 20 perfect surface on the various parts of the pot, all the surplus clay being carried away and the formation of burrs prevented, which could not be accomplished if the joint between the two rings 45 and 55 were in a 25 plane perpendicular to the axis of rotation of the spinner and the pot being formed.

I claim:

1. In a pot making machine, a forming ring and a relatively movable ring cooperating therewith, said rings having interfitting faces portions of which are at angles to a plane perpendicular to the axis of the ring.
2. In a pot making machine, a pair of relatively movable pot forming rings having 35 opposed interfitting faces portions of which are inclined with reference to planes perpendicular to the axis of the rings, and a spinner within said rings rotatable on said axis.
3. In a pot making machine a pair of relatively movable pot forming parts having 40 opposed irregular interfitting faces.
4. In a pot making machine, a pair of relatively movable pot forming parts having opposed irregular interfitting faces which 45 produce a temporary joint between them, and a spinner within the parts for rotating a pot with reference to the joint and past the irregular portions of said faces.
5. In a pot making machine, a spinner, a 50 forming member against which the spinner bears, and a second forming member movable relatively to the first mentioned member, said members having opposed faces adapted to interfit and form a joint, portions of said 55 joint being at an angle with reference to planes perpendicular to the axis of the spin-

ner, whereby said portions serve to clean the surface of the pot adjacent the joint.

6. In a pot making machine, a spinner, a forming ring against which the spinner bears, and a second ring movable relatively to the first mentioned ring, said rings having opposed irregular faces adapted to interfit and form an irregular joint presenting portions thereof at an angle to planes perpendicular to the axis of the spinner, whereby said portions serve to clean that portion of a pot adjacent the joint.

7. In a pot forming machine, a pair of irregular interfitting parts movable bodily toward and from one another along their common axis.

8. In a pot making machine, a forming ring, a spinner bearing against the ring and centered by the ring, and a second ring movable relatively to the first mentioned ring, said rings having opposed irregular faces adapted to interfit and form an irregular joint presenting portions thereof at an angle to planes perpendicular to the axis of the spinner, whereby said portions serve to clean that part of the pot surface adjacent the joint when the spinner causes the pot being formed to rotate within the rings.

9. In a pot making machine, a pair of irregular interfitting parts movable relatively to one another having vents adjacent their opposed faces.

10. In a pot making machine, a pair of relatively movable rings having opposed irregular interfitting faces and having vents formed therein at said faces.

11. In a pot making machine, a pair of opposed relatively movable rings having interfitting faces, vents being provided at said faces.

12. In a pot making machine, a pair of opposed relatively movable rings having opposed engaging faces and having vents at said faces.

13. In a pot making machine, a pair of opposed relatively movable rings having opposed interfitting irregular faces.

14. In a pot making machine, a pair of opposed relatively movable parts having interfitting irregular faces, means to rotate a pot within said parts, and means to move one of said parts towards the other along its axis.

In testimony whereof I affix my signature.

HARLEY H. MONTAGUE.
